UNITED STATES PATENT OFFICE.

LOUIS DE VAUX, OF ST. LOUIS, MISSOURI, ASSIGNOR OF TWO-THIRDS TO
F. H. DE VAUX, OF CHICAGO, ILLINOIS.

REFRIGERATOR.

SPECIFICATION forming part of Letters Patent No. 764,274, dated July 5, 1904.

Application filed August 17, 1903. Serial No. 169,796. (No model.)

To all whom it may concern:

Be it known that I, LOUIS DE VAUX, a citizen of the United States, residing at St. Louis, in the State of Missouri, have invented a new and useful Refrigerator, of which the following is a specification.

My invention relates to refrigerators; and it consists in the features hereinafter described and more particularly claimed.

10 In the accompanying drawings, Figure 1 is a central vertical section through one embodiment of my improved refrigerator. Fig. 2 is a full horizontal section on the line 2 2 of Fig. 1, and Fig. 3 is a top plan view with the 15 upper chamber removed.

Similar characters indicate like parts throughout the several figures of the drawings.

The letter C designates a casing, preferably 20 of cylindrical form and consisting conveniently of a cast-metal bottom plate 10, having supporting-legs 11, a cast top ring 12, and intermediate inner and outer walls 13 14, respectively, of sheet metal or other suitable mate-

25 rial, between which is an insulating-space 15. At one side of the casing is an opening in which is inserted a preferably cast door-frame 16, carrying a double or insulating door 17, and at the bottom of the casing is a drip-opening 18.

30 Within the casing, resting upon the bottom plate, is a drip-pan 19 of suitable depth, closely filling the casing, but readily removable therefrom through the opening at the top. It is provided with a drip-pipe 20, ex- 35 tending down through the opening 18 and upward for a convenient distance. At the center is bolted or otherwise secured a tubular casting or step-bearing 21, having at the bottom lateral opening 22. This pan is prefer-

40 ably covered by a plate 23, having a central opening registering with the step 21, and through the opening into the step, by which it is rotatably supported, extends the end of a shelf member S, comprising a central pipe 45 or tubular standard 24, stepped in the bearing and circular shelves 25, here shown as two in number, secured to the standard. If desired, the shelf-standard may have a separable sec-

tion 24^a, to which the upper shelf is secured. The lower shelf conveniently comes at or just 50 below the level of the door-opening and the other at such points as to be readily accessible through said opening. Above the shelves, preferably by lugs 26, projecting over the top ring 12, is supported an ice pan or receiver 27 55 of any suitable depth to contain the desired quantity of ice and conforming to the casing, but separated therefrom by an annular space 27^a to allow the descent of the cold air. This ice-pan may be held against too free upward 60 movement and in its correct lateral position by projections or loops 28, engaging the inside of the wall 13 below the ring. At its center is a depending drip-pipe 29, the outside of which serves as a bearing about which 65 turns the upper end of the shelf-standard 24. At the top of the casing, having a depending circular flange 30, extending within the ring 12, is a preferably cylindrical storage-chamber 31, access to which may be had through 70 an opening in its top, closed by a cover 32.

In use the chamber 31, which is adapted for the storage of materials not requiring as great a degree of cold for their preservation as those introduced through the door in the side 75 of the casing, is removed to permit the filling of the receiver with ice. The water therefrom descends through the shelf-standard out of the openings in the step and into the drip-pan, from which it escapes through the pipe 20. 80

It will be seen that all the interior portions of my improved refrigerator may be readily removed through the top of the casing for cleansing and repair and that it is compact and convenient of access. 85

Having thus described my invention, I claim—

1. A refrigerator comprising a casing, a drip-pan at the bottom of said casing, a step mounted in said drip-pan and having openings in the bottom thereof, a tubular standard rotatably mounted in said step and having openings at the bottom, shelves carried by said standard, a tubular member fitted in the top of said standard, a shelf attached to said 95 tubular member, and an ice-pan supported in

the top of said casing and having a pendent drip-pipe extending into the top of the tubular member mounted in said tubular standard.

2. A refrigerator comprising a casing, an
5 ice-pan removably supported in the top of said
casing and spaced from the casing-wall, means
for holding said ice-pan at constant distance
from the casing-wall, a drip-pipe extending
downwardly from said ice-pan, a drip-pan at
10 the bottom of said casing, a step in said pan,
a tubular standard rotatably mounted in said

step, shelves fixed upon said standard, and a
tubular connection between said tubular stand-
ard and said drip-pipe.

In testimony that I claim the foregoing as ¹⁵
my own I have hereto affixed my signature
in the presence of two witnesses.

LOUIS DE VAUX.
